Attorney

UNITED STATES PATENT OFFICE.

FRANK FUNK, OF BEVERLY, ILLINOIS.

WAGON-BED LIFTING-JACK.

SPECIFICATION forming part of Letters Patent No. 286,806, dated October 16, 1883.

Application filed September 8, 1883. (No model.)

To all whom it may concern:

Be it known that I, FRANK FUNK, a citizen of the United States, and a resident of Beverly, in the county of Adams and State of Illinois, have 5 invented certain new and useful Improvements in Wagon-Bed Lifting-Jacks; and I do hereby declare that the following is a full, clear, and exact description of the invention, which will enable others skilled in the art to which it applies to make and use the same, reference being had to the accompanying drawings, which form a part of this specification, and in which—

Figure 1 is a perspective view of my improved wagon-bed lifting-jack. Fig. 2 is a longitudinal vertical sectional view of one end of the same on line x x , Fig. 1. Fig. 3 is a perspective detail view of one of the friction-cams, and Fig. 4, is a similar view of one of the springs.

Similar letters of reference indicate corresponding parts in all the figures.

My invention has relation to wagon-bed lifting-jacks; and it consists in the improved construction and combination of parts of the same, 25 as will be hereinafter more fully described and claimed.

In the accompanying drawings, A represents the frame of my device, which consists of four 30 posts, A', connected at their tops by cross-pieces A'', which support a cross-beam, B, the ends of which extend out beyond the said cross-pieces. The outwardly-projecting ends of the cross-beam B are provided with longitudinal slots B', through which the holding- 35 rods pass.

C C indicate the holding-rod, each rod having hinged to its lower end an eyebolt, D, for the purpose hereinafter specified.

40 E E represent the friction-cams, one of which is shown in detail in Fig. 3 of the drawings, and which is provided with a head, E', central aperture, E'', through which the holding-rod passes, and extension F, having aperture F', to adapt the cam to be connected by means of a link, G, to staples H on the under side of each of the projecting ends of the cross-beam.

I I indicate the springs which are employed 45 in lowering the wagon, each spring consisting

of two stout curved wires, I', having their ends bent backward, and a coiled spring, I'', encircling the said wires between their bent ends, the springs being suspended by means of a staple to the under side of each of the outwardly-projecting ends of the cross-beam B.

The manner in which my improved wagon-bed lifting-jack is operated is as follows: When it is desired to lift the bed from the other portion of a wagon, the holding-rod, which are 60 pushed up out of the way when not in use, are drawn down, and the eyebolt on the lower end of each of the said rods is inserted through an aperture, K, suitably strengthened by plates K' in either end of the wagon-bed, a key, L, 65 being then placed through an aperture in the extremity of each eyebolt, for the purpose of preventing the bolt from slipping out while the wagon-bed is being raised or lowered. The wagon-bed may now be raised, one end at 70 a time when only one person is employed in the operation, the friction-cams E E serving to hold the rods C C to whatever height the wagon-bed may be raised. To lower the wagon-bed, the loop on the lower end of each of 75 the springs I is passed over the head E' of the friction-cams E E, thereby raising the outer end of each cam, so as to allow the holding-rod C C to slide freely through the said cams. To the outer end of each of the friction-cams 80 is attached a cord, M, which the operator allows to slide loosely through one of his hands while employing both hands in lowering the wagon-bed. By pulling down upon the said rope, the operator can lessen the rapidity of 85 the wagon bed's descent, or stop the descent altogether.

From the foregoing description, taken in connection with the accompanying drawings, the construction and manner of operating my 90 improved wagon-bed lifting-jack will readily be understood without requiring further explanation.

It will be seen that my improved wagon-bed lifting-jack is simple in construction, and, being devoid of all complicated parts, is not liable to break or get out of order.

By the use of my device one person can raise or lower a wagon-bed of any weight, in the manner previously described.

Having thus described my invention, I claim and desire to secure by Letters Patent of the United States—

In a wagon-bed lifting-jack of substantially the described construction, the combination of the frame A and cross-beam B, provided with the longitudinal slots B'B', friction-cams E E, having brake-cords M, and springs II, adapted to raise the outer end of the friction-cams when desired, with the holding-rod C C, having eye-bolts D D hinged to their lower ends, and adapted to slide through the central aperture

of the friction-cams and the longitudinal slots in the projecting ends of the cross-beam B, all constructed and arranged to operate substantially in the manner, and for the purpose shown and described. 15

In testimony that I claim the foregoing as my own I have hereunto affixed my signature in presence of two witnesses.

FRANK FUNK.
